CLAIM

The ornamental design for a modular cartridge assembly, as shown and described.

DESCRIPTION

FIG. 1 is a perspective view of a modular cartridge assembly showing the claimed design.

FIG. 2 is a front view of the modular cartridge assembly.

FIG. 3 is a rear view of the modular cartridge assembly.

FIG. 4 is a left side view of the modular cartridge assembly.

FIG. 5 is a right side view of the modular cartridge assembly.

FIG. 6 is a top view of the modular cartridge assembly; and,

FIG. 7 is a bottom view of the modular cartridge assembly. The broken lines show portions of the modular cartridge assembly that form no part of the claimed design.
